SOLID FEEDING MEANS FOR FLUID-TYPE PULVERIZER

Conrad Trost and Joseph William Holdcraft,
Moorestown, N. J., assignors, by mesne assignments,
to Freeport Sulphur Company, New York, N. Y., a corporation of Delaware

Application February 9, 1949, Serial No. 75,424

2 Claims. (Cl. 241—39)

1

This invention relates in general to a re-entrant circulatory pulverizer and more particularly to an improved method and means for feeding material into said pulverizer and grinding same whereby the operating efficiency and production capacity thereof are substantially increased.

It has been found as a result of both commercial practice and experimental tests that the production capacity, the operating efficiency and the range of use of presently known types of circulatory pulverizers or grinding mills, such as the one disclosed in the Andrews Patent Number 2,032,827, are limited by their means for feeding the material to be pulverized into the grinding chamber of the pulverizer. A commonly used material feeding means, hereinafter referred to as the "injection feeding tube," is comprised of a tube which connects a hopper to said grinding chamber. A gas or fluid, which is forced under pressure through said tube, entrains partially pulverized material falling from said hopper into the tube and conveys it into said grinding chamber. The injection feeding tube, whose general operation is well known to the art raises several problems. Sometimes it becomes plugged with the material being fed through it, especially when such material has a waxy texture or when it is fed too rapidly. Since there is a constant pressure within said grinding chamber, such a stoppage in the feeding tube will cause the material being pulverized in the chamber to back up said tube. This is referred to as a "blowback" and is very detrimental to the operating efficiency of the machine. Unsuccessful attempts have been made to overcome feeding tube stoppages by enlarging the tube. However, beyond a certain point, enlargement interferes in other respects with the operation of the pulverizer.

The feeding tube fluid, which is preferably the same as the grinding fluid emitted from the side walls of the grinding chamber, necessarily enters the grinding chamber at an angle to the path of the grinding fluid therein and thereby creates a considerable turbulence. It was once thought that turbulence contributes to the comminution of the solid material. Experiments, however, in which the various factors contributing to pulverization were studied photographically, showed that turbulence caused practically no comminution, whereas its disadvantages effects, such as excessive wear, "kickbacks" and lost energy, definitely limit the productivity of the pulverizer.

As disclosed in said Andrews Patent No. 2,032,827, the maintenance of a uniform vortex of circulating fluid in the grinding chamber is necessary for efficient pulverizing and classifying action upon the solid material. It has been found that material introduced by the injection feeding tube, or by other methods heretofore used, enters the vortex erratically and usually with instantaneous bursts due to alternate build-up and re-

2

lease through the tube entrance to the grinding chamber. This causes distortion of the inwardly spiralling vortex and the resultant turbulence causes entrainment of oversized particles in the exhaust gases from said chamber. This effect is especially noticeable at higher rates of operation.

It becomes apparent therefore, that the injection feeding tube means of supplying solid material to the grinding chamber is unsatisfactory because it limits the productivity of the pulverizer by creating a wasteful turbulence and by frequent stoppages.

It has also been found that the feeding tube fluid, which constitutes between 15% and 30% of the fluid circling in the grinding chamber, is considerably decelerated during the entrainment and acceleration of the solid material conveyed thereby. Therefore, much energy is expended by the grinding fluid in accelerating the feeding tube fluid, which energy might otherwise be used to pulverize additional solid material. This energy loss exists in addition to the losses arising from the turbulence created in the grinding chamber and the resultant disturbance of the vortex pattern of the grinding fluid.

Therefore, a need becomes apparent for an improved means and method of introducing solid material, which may be partially comminuted, into the grinding chamber of a circulatory pulverizer without the encumbrance of the feeding tube fluid which materially reduces the efficiency and capacity of the pulverizer.

The same above cited problems are encountered in all circulatory type pulverizers using the injection method of feeding the partially comminuted material, whether they are of the circular or oval, open center or tubular ring type, and the scope of this invention in its broadest aspects is intended to apply to all such pulverizers.

Accordingly, it is a primary object of this invention to provide an improved method and means for feeding solid material into the grinding chamber of a circulatory type of pulverizer or mill, whereby the production capacity and operating efficiency of the pulverizer may be substantially increased beyond the capacity and efficiency obtainable with presently known types of solid material feeding means and methods.

A further object of this invention is to provide an improved method and means, as aforesaid, whereby the range of use of a circulatory type pulverizer may be expanded to include materials, such as the waxy and amorphous types, which cannot now be effectively pulverized in mills equipped with presently known types of material feeding means.

A further object of this invention is to provide an improved method and means, as aforesaid, whereby the amount of pressurized fluid required to operate a given pulverizer at peak output may be substantially reduced without decreasing the yield of the pulverizer.

A further object of this invention is to provide an improved method and means, as aforesaid, whereby the turbulence incident to the injection method of feeding the solid material into the grinding chamber is greatly reduced or substantially eliminated, thereby removing the excessive energy losses and wear of the grinding chamber walls which accompany such turbulence.

A further object of this invention is to provide an improved method and means, as aforesaid, which does not disturb the vortex action within the grinding chamber, which action effects a classification of the pulverized particles wherein the larger particles continue to circle near the outer perimeter of the chamber whereas the smaller particles move toward the center and are drawn off by the exhausting fluid.

Other objects and purposes of this invention will become apparent to persons familiar with this type of equipment upon referring to the accompanying drawings and upon reading the following specification.

In order to meet those objects and purposes heretofore mentioned, as well as others incidental thereto and associated therewith, we have provided a mechanical feeding device which, in one preferred embodiment, is comprised of a tube communicating between a materials hopper and the grinding chamber. The material is moved from the hopper to the grinding chamber by a screw which is rotatably supported snugly within said tube. The end of the screw adjacent to the grinding chamber is spaced sufficiently away from said chamber that the mouth of the tube may be choked and thereby assure that the material will enter the grinding chamber in a solid mass. Normally, the mouth of the tube is slightly constricted to effect such choking. A means is provided for rotating the screw and thereby feeding a continuous mass of material through the said tube mouth.

The leading portion of the solid mass of material is preferably struck by grinding fluid emitted from a jet in the grinding chamber peripheral wall and directed at said mass as it protrudes through the mouth of the feeding tube. Thus, the said entering face of said mass is eroded, or abraded, both by the rapidly moving grinding fluid from said jet and by the particles of material which have earlier been broken away from said solid mass by said jet and entrained in the circulating grinding fluid. The solid mass may be fed into the chamber at a constant, controlled rate which creates little or no disturbance within the grinding chamber.

For illustrations of the improved feeding device to which this invention relates, attention is directed to the accompanying drawings in which:

Figure 1 is a broken and partially sectioned side elevation view of a conventional circulatory pulverizer provided without improved mechanical feeding device.

Figure 2 is a fragmentary view of a portion of said pulverizer and a modified type of mechanical feeding device.

Figure 3 is a fragmentary view of the stuffing box and bearing indicated in Figure 1 but shown on an enlarged scale.

CONSTRUCTION

The embodiment of my invention illustrated in Figure 1 of the accompanying drawings is shown, by way of example, in cooperation with a conventional reentrant circulatory pulverizer 10 of the general type, excepting for the feeding means,

illustrated in the above mentioned Andrews patent. It has a cylindrical grinding chamber 11 which is surrounded, adjacent to its circumferential wall 12, by an annular header 13. The pulverizer 10 is provided with a pair of flat parallel plates 14 and 15 which intersect the axis of the pulverizer 10 perpendicularly. The circumferential wall 12 is provided with a plurality of jet openings 16 which communicate between the annular header 13 and the grinding chamber 11, and which are preferably so positioned that the paths of the fluid emitted from said jets are substantially tangent to one or more circles about the axis of the grinding chamber 11 in a manner well known and well established in the art.

An offtake pipe 17, which is preferably coaxial with the cylindrical grinding chamber 11 extends into said grinding chamber through a suitable opening in one of the plates, here the plate 14, of the pulverizer 10. The grinding fluid and sufficiently pulverized particles entrained thereby escape through the offtake pipe 17 and are conveyed to suitable separating means (not shown) in the conventional manner. A suitable grinding fluid, such as compressed air or steam, is supplied under pressure to the annular header 13 from an appropriate source (not shown) through the supply pipe 18.

The mechanical feeding device 22, to which this invention relates, includes a feeder tube 21 (Figure 1) which at one end extends through a suitable opening in the plate 14 of the reentrant circulatory pulverizer 10 so that said tube communicates with the grinding chamber 11. The said one end of the feeder tube 21 preferably does not extend beyond the inner surface 23 of the plate 14, and is advantageously provided with an annular, internal ridge 24 which restricts the opening of the feeder tube 21 adjacent to the grinding chamber. The ridge may be increased or decreased in size, or in some cases may be eliminated entirely, according to the natural cohesiveness of the material being ground. The less the natural cohesiveness the larger the ridge must be. In any event, it should be of such size as to insure that the material is compacted before it enters the grinding chamber.

However, since the feeder screw displaces a certain amount of the solid material throughout that portion of the feeder chamber in which said screw is positioned, the chamber mouth is preferably choked down by at least an amount corresponding to the displaced area of the screw thereby effecting an even and constant flow of solid material through the mouth 25.

It will be clearly understood that the exact size or shape of the mouth 25 provided by the annular ridge 24 is not intended to impose any limitations upon this invention, for these will vary according to the cohesiveness of the particular materials involved and the feed rates used providing only that the material is fed into said chamber in a solid, compacted mass.

The exact point at which, and the angle with which, the feeder tube 21 communicates with the grinding chamber 11 may be varied from that which is shown in the illustrations without departing from the scope of the invention. The tube 21 may communicate with the chamber 11 either through one of the plates 14 or 15 or through the circumferential wall 12 and more than one feeder tube may be used with a single grinding chamber. Generally, however, it seems preferable in most instances to have the tube 21 communicate with the chamber 11 through one of

said plates 14 and 15 and be substantially perpendicular thereto at the circle of maximum velocity of the grinding fluid. In the type of grinder illustrated by the above mentioned Andrews patent, this circle is approximately tangent to the path of the grinding fluid emitted from said jets. Further, it seems to be of some importance whereon said circle, especially with relation to the grinding jets, the tube mouth 25 is located, it being normally advantageous to have a grinding jet impinge substantially directly upon the plug as it protrudes from said mouth. Under some circumstances, such as where the material to be pulverized is either very cohesive or relatively hard, it is practically imperative that this direct impingement be provided.

A feeder screw 26 is rotatably and snugly housed within the tube 21 so that the inner end 27 thereof, adjacent to the pulverizer 10, approaches but does not extend through the mouth 25 into the grinding chamber 11. Said inner end 27 of the screw 26 is preferably, but not necessarily, inclined to the axis of the said screw. The outer end 28 of said screw 26 is important that direct impingement by a jet be provided with a screw plate 30 which is secured to, or is integral with, a coaxial shaft 29 extending out of the end 31 of the feeder tube 21 remote from the pulverizer 10. Suitable means, such as an adjustable stuffing box 32 of any conventional type may be supported upon the end 31 of the tube 21 and encircle the shaft 29 in a conventional manner to prevent the escape of grinding fluid through the end 31 of said feeding tube before material being fed therethrough is formed into a solid mass.

In this embodiment of the invention, the stuffing box 32 (Figure 3) is comprised of a flanged cylindrical housing 33 threadedly engaging the tube end 31, a flanged gland 34, and suitable packing 35. The gland 34 is urged toward the housing 33 by conventional means, such as the bolt and nut arrangement 36, thereby compressing the packing 35 against the shaft 29 and effecting a seal therearound.

The shaft 29 may be rotatably supported upon a base 37 by any convenient, conventional bearings 38. A gear pinion 39 may be secured upon said shaft between said bearings 38 for rotation thereof by any suitable means (not shown).

The screw 26 and the shaft 29 may be adjusted axially toward or away from the pulverizer 10 by any convenient means. One operable means of accomplishing this axial adjustment is comprised of a pair of spaced thrust collars 41 and 42 secured to that end of the shaft 29 remote from the screw 26, and a thrust head 43 surrounding said collar 41 and entering the space between the collars 41 and 42. An externally threaded adjustment screw 44, which is coaxial with said shaft 29 is secured to the thrust head 43 at one end thereof and to a crank 45 at the other end thereof. The screw 44 is threadedly engaged by and extends through an adjustment post 46 which is supported upon the base 37.

Accordingly, rotation of the adjustment screw 44 by the crank 45 in one direction causes said head 43 to bear against the collar 42 and thereby urge the shaft 29, hence the screw 26, toward the pulverizer 10. Rotation of the screw 44 in the opposite direction causes said head 43 to bear against the collar 41 and thereby draw the shaft 29, hence the screw 26, away from the pulverizer 10.

A materials hopper 47 communicates with the cylindrical feeder chamber 48 within the feeder

tube 21 through a suitable opening therein intermediate the extremities thereof. The screw plate 30 inhibits the escape of the material into the stuffing box.

Material to be pulverized, which may be in a granulated, or other partially comminuted condition, is placed in the hopper 47 and conveyed by the screw 26 through the chamber 48 into the grinding chamber 11.

10

MODIFICATIONS

A modified mechanical feeding device 51, illustrated in Figure 2, is comprised of a feeder tube 52 which is substantially identical to the feeder tube 21 (Figure 1). However, in this modification, the feeder screw 26 and the associated actuating mechanism are replaced by a plunger 53, which is actuated toward and away from the grinding chamber 11a by any suitable and conventional means (not shown) such as a hydraulic pressure device. This type of mechanical feeding device is somewhat limited in its operation in that it cannot of itself affect a continuous feed of material into said grinding chamber but it avoids the expense and problems of screw feed operations. However, if two or more of said modified devices 51 are used in conjunction with the same pulverizer, a substantially continuous operation may be accomplished by operating them alternately. It will be recognized, therefore, that although the mechanical feeding device 22 and the modified device 51 are specific embodiments of the invention which can accomplish the desired result, other modifications will be found to lie within the broadest scope contemplated by this invention.

OPERATION

The material to be pulverized, which may be partially preground or otherwise partially comminuted, is placed within the hopper 47, the feeder screw 26 is rotated until the material or feed is conveyed through the feeder chamber 48 to the mouth 25 of the feeder tube 21. Where the material is not sufficiently cohesive to form the solid mass readily, the mouth 25 may be choked by means of the ridge 24 and the screw 26 may be initially run at a higher rate of speed than normal in order to start the formation of the mass, or the material may be initially treated with some cohering agent, such as water or oil, to assist in initially forming a solid mass. In any event, the screw will be started a few seconds before the grinding fluid is released into the grinding chamber to assure that the plug is well formed before the grinding chamber pressure is imposed upon it. The pressure behind the grinding fluid, which flows through the supply pipe 18 into the annular header 13, is gradually increased as said fluid flows into the grinding chamber 11 where it soon circulates therein at a high rate of speed. As the material is fed by the screw 26 through the feeder tube 21 it is compacted into a solid mass and emerges through the mouth 25 in such form.

The further the screw 26 is from the chamber 11, the greater the torque becomes upon said screw to force the material through the mouth 25. However, it has been found that the material in the tube 21 resists the back pressure of the grinding chamber 11 more effectively when the screw 26 is rather substantially spaced from said grinding chamber in order to permit the formation of a sufficiently long and solid plug at the mouth of the tube to block the escape of grinding

75

fluid therethrough. Therefore, the screw is moved back from the mouth 25 while the speed and circulating load of the fluid and material are being built up, during which time the static pressure within the chamber 11 is highest and the material in the tube is relatively, loosely packed and least resistant to back pressure. As the speed of the fluid and load increases and the static pressure in the grinding chamber decreases, the screw 26 is moved toward the chamber until at 10 full operating speed the screw is as close to the mouth 25 as possible without permitting the escape of grinding fluid through said feed tube 21.

The grinding fluid emitted from said impinging jet and/or circulating in the chamber 11 strikes the mass of material as it protrudes through the mouth 25 breaking off particles of the material in an abrading type of action. These particles are then further struck by the grinding jets and otherwise handled in the grinding chamber in the manner fully disclosed in the aforesaid Andrews Patent No. 2,043,827. It will be clearly recognized that substantially the entire energy of the grinding fluid emitted through the jet opening 16 is absorbed in the abrasion of the solid mass emerging through the mouth 25, and in the acceleration, circulation, comminution and offtake of the particles abrading from said mass. None of the grinding fluid energy is dissipated in turbulence caused by, or in the need for accelerating, any other material, such as the gas of the conventional injection type feeder.

The rate of feeding is controlled so that the exposed surface of the solid mass is at all times nearly flush with the adjacent wall of the grinding chamber. Thus, the protrusion of the solid mass into the grinding chamber is at all times sufficiently small that the turbulence created thereby in the grinding stream is negligible. However, due to the higher efficiency of this method of feeding and grinding, the feed rate in any given case will actually be higher than for conventional injection feeding under similar conditions. Furthermore, the mechanical feeding device does not disturb or upset the vortex action which moves the sufficiently small particles of pulverized material toward the exhaust pipe 17 and tends to hold the large particles near the radially outer portion of the grinding chamber where they may be exposed to further comminution, particularly by the cutting force of the grinding fluid emitted through the jets 16.

EXPERIMENTAL DATA.

The following examples are typical examples of the operation of a pulverizer equipped with an improved mechanical feeding device to which this invention relates.

Example I

A fifteen inch diameter reentrant circulatory pulverizing mill of conventional type was fitted with a mechanical feeding device having a screw feeder as shown in Figure 1. The screw was eighteen inches long and two inches in diameter, and had a screw pitch of 4 inches. The distance from the screw inner end 27 to the plate inner surface 23, which in this particular machine may be varied from 1 1/4 inches to 3 1/4 inches was first held so that said screw inner end 27 was about as far away from said wall inner surface 23 as the adjustable stuffing box 32 would permit for reasons hereinabove described. The hopper 47, which was positioned approximately ten inches from the plate 14, had a 4-inch opening in its

lower end communicating with the feeder chamber 48. The end 27 of the feeder screw was cut at an angle of about 70 degrees to the axis of the screw 26 to facilitate the feeding action.

It was found advisable to start the circulating of the grinding fluid in the grinding chamber by slowly but steadily increasing the pressure behind the grinding fluid emitted through the jets 16. At this time the back pressure within the feeder tube was from five to seven pounds per square inch or more, while the grinding chamber 11 was substantially empty. As the load of circulating fluid and material in the pulverizing grinding chamber increased, the back pressure decreased from two to four pounds per square inch. Therefore, it was found desirable to maintain a relatively large space between the end of the screw 27 and the wall inner face 23 while the pulverizing machine was starting in order to place a larger amount of material in the mouth 25 and thereby prevent a blow back during this period. As the speed and load of the machine were increased, and the back pressure reduced accordingly, the feeder screw was moved toward the pulverizing chamber, thereby reducing the amount of power required to urge the feed material through the mouth 25.

The feed material, consisting in this example of partially comminuted sulphur ranging in size from 1/4 inch in diameter to less than 50 mesh, was fed by the feeder screw 26 into the grinding chamber 11 at a rate of 437 pounds per hour. The feeder screw 26 was rotated at 175 R. P. M. and required 0.2 amps. at 110 volts of alternating current. Air, under a pressure of 100 pounds per square inch, was supplied to the annular header 13 from whence it was emitted through the jet openings 16 at a rate 286 C. F. M. free air. The average particle size of the product carried off through the exhaust pipe 17 was 3.2 microns, said product containing less than 0.01 per cent of particles larger than 325 mesh.

Example II

The data in the following table was obtained in tests of the commercial type, 24 inch diameter reentrant circulatory pulverizer as disclosed in the Andrews Patent No. 2,032,827. The pulverizer was first operated in a conventional manner with an injector feed mechanism such as shown in the above mentioned patent. This injection feed mechanism was then replaced with the mechanical feeding device 22 (Figure 1). The material with which the pulverizing unit was charged consisted of a partially pulverized hard talc, 99.1 per cent of which could pass through a 325 mesh screen and had an average particle size of 1.8 microns. The following table indicates the relative capacities and efficiency of the two types of feeding mechanism, both of which were used under as nearly identical and optimum conditions as possible:

TABLE I

	Injection Feed	Mechanical Feed
Air Pressure (p. s. i.)	100	100
C. F. M. (Free Air)	1,080	899
Feed Rate (lbs. per hr.)	1,000	1,780
Average Size of Product (Microns)	1.55	1.40
C. F. M. of air per lb. of feed per hr.	1.98	.45
Lbs. handled per cubic ft. (Free air)	0.01544	.0371

It will be noted from Table I that the mechanical feeding mechanism increased the capacity of

the pulverizer, which was operated at maximum output with both feeding mechanisms, by 78 per cent while decreasing the quantity of air required by 26 per cent. The pulverizer, when operated with the mechanical feeding device, demonstrated an overall increase in efficiency of about 140 per cent over the efficiency of the pulverizer equipped with the injection feed mechanism, while the average size of the product was decreased approximately 10 per cent.

The following table represents the results of another test on a commercial mill of the type shown in said Andrews patent, operated at maximum output first with a conventional injection type feed mechanism and then with the screw-type mechanical feed device above described to pulverize precrushed talc of 100 mesh size:

TABLE II

	Injection Feed	Mechanical Feed
Air Pressure (p. s. i.)	100	100
C. F. M. (Free Air)	1,000	800
Feed Rate (lbs. per hour)	800	1,800
Average Size of Product (Microns)	2.0	2.0
C. F. M. of air per lb. of feed per hr.	1.25	.44
Lbs. of material per cubic ft. free air	0.0133	0.03755

It can be seen from the above table that the mechanical feed device increased the productive capacity of the mill by 125 per cent while the efficiency of the compressed air used was increased by more than 175 per cent.

It will be noted that a substantial saving, namely 200 C. F. M., in the amount of compressed air actually required is made when the improved type feeding unit is used. This is 20 per cent of the air used with the injection system and means that about 1000 pounds of air per hour is eliminated from the grinding chamber. As much energy is required to accelerate this 1000 pounds of air to the very high velocities inside the grinding mill as is required to accelerate 1000 pounds of feed material. Therefore, it is believed that the increase of 1000 pounds per hour in the yield of pulverized material is substantially due to the elimination of the air used in the injection system, which in this particular case would amount to about 1000 pounds by weight.

Table III was recorded from a test of a commercial mill of the same size and type used for the above tables. It was operated at maximum output with both feeding mechanisms, in which a 50% DDT composition, having a particle size of about 90% less than 100 mesh, was pulverized:

TABLE III

	Injection Feed	Mechanical Feed
Air Pressure (p. s. i.)	100	100
C. F. M. (Free Air)	1,080	800
Feed Rate (lbs. per hour)	975	1,300
Average Size of Product (Microns)	2.5	2.2
C. F. M. of air per lb. of feed per hr.	1.11	.61
Lbs. of material per cubic ft. free air	0.0151	0.0272

The increase in capacity of the mill obtained with the mechanical feeding device in the foregoing test amounted to about 35% over the mill capacity with the injection feed device. The increase in fluid efficiency, that is the increase in pounds of material ground per cubic foot of air used, obtained with the mechanical feeding device amounted to about 80% over the mill capacity with the injection feed device.

Although the above mentioned drawings and description apply to one particular preferred embodiment of the invention, it is not my intention, implied or otherwise to eliminate other variations or modifications of my improved mechanical feeding mechanism which will accomplish the desired result while remaining within the scope of the invention, unless specifically stated to the contrary in the hereinafter appended claims.

10 We claim:

1. In a device for compacting and feeding a mass of partially comminuted material into the grinding chamber of a fluid, circulatory pulverizer in which a grinding fluid is circulated, the combination comprising: a tube having a cylindrical feed chamber communicating at one end thereof with the grinding chamber, the adjacent end of said tube stopping short of said grinding chamber; a closure means disposed within the other end of said feed chamber and a hopper communicating with said feed chamber intermediate the ends thereof; a screw rotatably and axially reciprocably supported within said feed chamber, and spaced from said grinding chamber; means, including a shaft extending through said closure and secured to said screw for effecting rotation and for axial adjustment thereof with respect to said grinding chamber; and an annular ridge extending internally from the walls of said feed chamber adjacent to said one end thereof, the area defined by said ridge being equal to the cross-sectional area of said feed chamber less the area absorbed by said screw, whereby said mass of material will have a substantially constant density throughout said feed chamber and will present an unbroken front as it enters said grinding chamber.

2. In a mechanical device for compacting and feeding a homogeneous mass of partially comminuted material through an opening in the sidewall of the grinding chamber of a fluid, re-entrant, circulatory pulverizer in which a grinding fluid is circulated, the combination comprising: a tube having a cylindrical feed chamber of constant diameter communicating at one end thereof with said grinding chamber through said opening, the adjacent end of said tube being flush with the inner surface of said sidewall; a closure means disposed within the other end of said feed chamber and a hopper communicating with said feed chamber intermediate the ends thereof; a screw rotatably, and axially adjustably, supported within said feed chamber, said screw being spaced from said grinding chamber; means, including a shaft secured to that end of said screw remote from said grinding chamber and extending through said closure, for rotating said screw and for effecting axial adjustment thereof with respect to said grinding chamber; and an annular ridge extending internally from the walls of said feed chamber adjacent to said one end thereof, the area defined by said ridge being equal to the cross-sectional area of said feed chamber less the area absorbed by said screw, whereby said mass of material will have a substantially constant density throughout said feed chamber and will present an unbroken front as it enters said grinding chamber.
